CLAIM

The ornamental design for a massage tool, as shown and described.

DESCRIPTION

FIG. 1 is a perspective view of a massage tool according to the claimed design.

FIG. 2 is a front view of the massage tool.

FIG. 3 is a rear view of the massage tool.

FIG. 4 is a top view of the massage tool.

FIG. 5 is a bottom view of the massage tool.

FIG. 6 is a right side view of the massage tool; and,

FIG. 7 is a left side view of the massage tool.

The surface line shading in the drawings shows surface contour and does not illustrate surface ornamentation.

1 Claim, 7 Drawing Sheets
